[57] CLAIM

The ornamental design for pegboard hook, as shown and described.

DESCRIPTION

FIG. 1 is a front isometric view of the pegboard hook, showing my new design;

FIG. 2 is a front elevational view thereof;

FIG. 3 is a rear elevational view thereof;

FIG. 4 is a right side elevational view thereof with the left side being identical but reversed;

FIG. 5 is a top plan view;

FIG. 6 is a bottom plan view thereof; and,

FIG. 7 is a front isometric view similar to FIG. 1 but of a modified form of the pegboard hook.

The appearance of the rear view of the second embodiment is similar to the rear view of the first embodiment except for the decreased dimension of the back panel.
